UNITED STATES PATENT OFFICE.

DAVID R. BRUCE, OF PONDERS END, ENGLAND.

AUTOMATIC ELECTRICAL CUT-OUT.

SPECIFICATION forming part of Letters Patent No. 731,428, dated June 23, 1903.

Application filed November 18, 1902. Serial No. 131,805. (No model.)

To all whom it may concern:

Be it known that I, DAVID ROBERTSON BRUCE, a citizen of England, residing at 2 Cottswell Villas, Hertford road, Ponders End, 5 in the county of Middlesex, England, have invented a certain new and useful Automatic Electrical Cut-Out, of which the following is a specification.

My invention relates to an automatic electrical cut-out, which I will describe, referring to the accompanying drawings, in which—

Figure 1 is a vertical longitudinal section, and Fig. 2 a plan.

A tube of non-conducting material *a* is provided with a conductor *i*, which is free to move longitudinally therein. This conductor has at one end an arm *b*, of conducting material, projecting outside the tube *a* and secured on the conductor by means of a nut *w*. 15 This arm *b* is hinged to an insulated metal piece *c* on a base-plate *d*, the hinge being provided with a spring *e*, which urges the other end of the tube *a* away from the base *d*. This spring *e* can be a blade-spring, as 20 shown, or may be a spring arranged in the hinge *c'*. The other end of the conductor *i* is enlarged beyond the tube *a*, so as to form an arm *f*, also of conducting material, which is provided with an arm projecting down- 25 ward, forming a hook *x*, that is engaged with a catch *g*, pivoted to another insulating-piece *h* on the base *d*. The arms *b* and *f* are formed with lugs *j* and *k*, respectively, on each side, in which are secured the conducting- 30 brushes *l l m m* by means of set-screws *n n o o*. These conducting-brushes bear on two insulated contact-pieces *p q*, fixed on the base, which form terminals, to which are attached at *s* and *t* the two parts of the conduct- 35 tors to which the cut-out is applied. The current consequently passes from brushes *l* through arm *b*, conductor *i*, arm *f*, and brushes *m m* to contact *q*. The catch *g* forms one arm of a bell-crank lever mounted in the 40 piece *h*, the other arm *g'* of which can be pressed, more or less, down by means of an adjusting-screw *u*, so that the catch *g* can be made to engage to a greater or less extent with the hook *x*, pivoted to the arm *f*. The 45 arm *g'* is kept in its normal position by a spring *v* and is provided with a button for re- 50 leasing the catch *g* by hand when necessary.

When a current passes through the conductor *i*, it heats it, causing it and its arms *b* and *f* to expand, and when the current is excessive the corresponding increased expansion causes the arm *f* to travel outward in a horizontal direction, thus causing the hook *x* to release itself from the catch *g*, whereupon the spring *e* at the hinge of the other arm *b* causes the tube to spring up, breaking contact. 55

In order to regulate this cut-out so as to act for currents of greater or less intensity, the hook *x* on *f* and the catch *g* are caused to take greater or less hold of one another, so that when the cut-out is to be used for currents of greater intensity these parts are fully engaged together and for a current of less intensity they are only slightly engaged together, and the amount to which they are engaged may be indicated by means of divisions on the adjusting-screw *u*. 60

Having now particularly described the nature of this invention and the best means I know of carrying the same into practical effect, I claim—

1. An automatic electric cut-out consisting of a tube of insulating material, a conductor passing through said tube having enlarged 65 ends projecting beyond the tube constituting conducting-arms, devices on each of said arms making contact respectively with one of the terminals of the circuit to be controlled, the one arm being pivoted to an insulated base and the other arm being provided with a hook adapted to engage with a pivoted insulated catch so that on the expansion of the conductor due to heating by excessive current, it will push the hook out of engagement 70 with the catch and a spring device whereby when such disengagement takes place, the tube with the conductor and its one arm are turned on the pivoted arm so as to break contact, substantially as described. 75

2. In an automatic electrical cut-out, the combination of a conductor free to expand longitudinally in one direction and having contact-brushes at both ends, a spring arranged to disengage the brushes, and a catch 80 arranged to be disengaged by expansion of the conductor under the heat of the current; substantially as described. 85

3. In an automatic electrical cut-out, the

combination of a conductor hinged at one end, insulating material surrounding the conductor, contact-brushes attached at both ends of the conductor, a spring arranged to disengage both brushes, and a catch adapted to be disengaged by longitudinal expansion of the conductor under the heat of the current; substantially as described.

4. In an automatic electrical cut-out, the combination of a conductor hinged at one end and having an insulating-casing, contact-brushes attached to both ends of the conductor, a spring arranged to disengage the

brushes, a catch arranged to be disengaged by longitudinal expansion of the conductor under the heat of the current, and means for adjusting the catch to change its point of disengaging; substantially as described.

In testimony whereof I have hereunto set my hand in presence of two subscribing witnesses.

D. R. BRUCE.
